Primary Examiner — George D Kirschbaum*Assistant Examiner* — Jennifer Watkins(74) *Attorney, Agent, or Firm* — Stephan A. Pendorf; Patent Central LLC(57) **CLAIM**

The ornamental design for a vibrational training board, as shown and described.

DESCRIPTION

FIG. 1 is a left, elevated, front perspective view of a vibrational training board showing my new design.

FIG. 2 is a front view thereof.

FIG. 3 is a rear view thereof.

FIG. 4 is a right side view thereof.

FIG. 5 is a left side view thereof.

FIG. 6 is a top view thereof, and,

FIG. 7 is a bottom view thereof.

The broken lines in FIG. 3 represent portions of a receptacle for an external power cord and form no part of the claim.
